W. B. WETMUR.

SAFETY RAZOR.

APPLICATION FILED JUNE 21, 1909.

949,205.

Patented Feb. 15, 1910.

UNITED STATES PATENT OFFICE.

WILLIAM B. WETMUR, OF MONTROSE, PENNSYLVANIA.

SAFETY-RAZOR.

949,205.

Specification of Letters Patent. Patented Feb. 15, 1910.

Application filed June 21, 1909. Serial No. 503,447.

To all whom it may concern:

Be it known that I, WILLIAM B. WETMUR, a citizen of the United States, residing at Montrose, in the county of Susquehanna, State of Pennsylvania, have invented certain new and useful Improvements in Safety-Razors; and I do hereby declare the following to be a full, clear, and exact description of the invention, such as will enable others skilled in the art to which it appertains to make and use the same.

This invention relates to safety razors, and has for one of its objects to improve the construction and increase the efficiency and utility of devices of this character.

Another object of the invention is to provide a simply constructed device wherein adjustable guard plates are employed so that as the blade is worn away the guard plates can be adjusted in accordance with the change of form of the blade.

With these and other objects in view, the invention consists in certain novel features of construction as hereafter shown and described and then specifically pointed out in the claims, and in the drawings illustrative of the preferred embodiment of the invention, Figure 1 is a side elevation of the improved device. Fig. 2 is a plan view of the same. Fig. 3 is an end elevation. Fig. 4 is a section enlarged on the line 4-4 of Fig. 2. Fig. 5 is a perspective view of the base member detached. Fig. 6 is a perspective view of the blade detached. Fig. 7 represents the two-part guard plate in perspective and detached. Fig. 8 is a perspective view of the clamp plate detached. Fig. 9 is a perspective view of a modified form of the two-part guard plate. Fig. 10 is a perspective view of the modified form of the clamp plate which will be employed with the modified form of the guard plate shown in Fig. 9.

The improved device comprises a base plate or member 10, preferably diamond shaped and with a concaved upper face and a convexed lower face and provided with upwardly directed studs 11-12 at the ends and a threaded stud 13 extending vertically from the center of the base plate. The blade is represented at 14 in Fig. 6, and is preferably formed with a convex lower face to conform to the convexed base plate, and is likewise provided with recesses 15-16 at its ends to engage with the studs 11-12, and is also provided with a central aperture 17 through which the stud 13 extends.

Bearing upon the plate 14 is a two-part guard member formed of two relatively thin plates 18-19 with recesses 20-21 in their confronting edges adapted to fit around the threaded stud 13. The outer edges of the guard members 18-19 are provided with spaced guard teeth or fingers 22-23 of the usual form. Rising from the plate 18 are spaced studs 24, and rising from the plate 19 are similar spaced studs 25, the studs 24-25 being arranged in alinement transversely of the guard plates, as shown. A clamp plate 26 having spaced slots 27 through which the studs 24-25 extend, and likewise provided with an aperture 23 through which the stud 13 extends, bears upon the plates. The handle member of the improved device is represented at 28 and is provided with a threaded aperture in its lower end adapted to engage over the threaded stud 13, and thus form a clamping means whereby the members of the device may be firmly compressed and held in position. By this simple means it will be obvious that the plates 18-19 may be adjusted toward and away from each other to conform to the position of the cutting edges of the blade 14 by simply loosening the handle 28 which will release the blades and permit the requisite adjustment. Thus when the blade 14 requires regrounding, the plates 18-19 may be readily adjusted to the change of location of the cutting edges, as will be obvious. In event of one of the cutting edges becoming "nicked", the plate can be ground to remove the nick, and the plates 18-19 then adjusted to a still greater extent to locate the fingers 22-23 in the proper position relative to the change of form of the newly ground cutting edge. With this improved device if the "nick" be near one end of the blade, the blade may be reground at an incline, or just sufficient to remove the nick, and thus avoid the necessity for cutting away the uninjured portion of the blade, and the guard plate adjusted at a corresponding incline, the slots 27, and the pins 24-25 being sufficiently loose to permit this slight oblique adjustment.

In Figs. 9 and 10 a slight modification in the construction is shown consisting in arranging the pins 24-25 in staggered relations, or out of alinement transversely, and forming the slots 27 likewise in staggered relations. This modification in the construction of the device may be advantageous under certain circumstances, but it will be

obvious that this slight modified form does not constitute a departure from the invention, or sacrifice any of its advantages, as the operation of the device produces the same result in both forms of the device.

What is claimed is:—

1. A safety razor comprising a base member having a threaded stud, a blade bearing upon said base and over said stud, a two-part guard member bearing upon said blade and provided with guide studs, a clamp plate bearing upon said guard plates and provided with slots through which said guide studs extend, and a handle having a threaded aperture engaging said guide stud and clamping the parts together.

2. A safety razor comprising a base member having a concaved upper face and a convexed lower face and with upwardly

directed studs at the ends and a threaded stud extending therefrom intermediate the ends, a blade having a convex lower face and bearing upon the concaved face of said base and over said stud, a two-part guard member bearing upon said blade and provided with guide studs, a clamp plate bearing upon said guard plates and provided with slots through which said guide studs extend, and a handle having a threaded aperture engaging said guide stud and clamping the parts together.

In testimony whereof, I affix my signature, in presence of two witnesses.

WILLIAM B. WETMUR.
